GUSTAVE FRANZ SCHMIDT, OF CHICAGO, ILLINOIS.

CARBURETING APPARATUS.

1,109,085.

Specification of Letters Patent.

Patented Sept. 1, 1914.

Continuation of application Serial No. 488,896, filed April 9, 1909. This application filed July 25, 1911. Serial No. 640,420.

To all whom it may concern:

Be it known that I, GUSTAVE F. SCHMIDT, at present residing in the city of Chicago, county of Cook, and State of Illinois, have 5 invented certain new and useful Improvements in Carbureting Apparatus, of which the following is a specification.

My invention relates to certain new and useful improvements in that type of carbureting apparatus adapted to generate gaseous fluid from gasolene and other similar hydro-carbon fluids.

In its generic nature, the invention has for its object to provide an apparatus where- 15 in exact measured quantities of gasolene are admitted into a more or less evacuated chamber where the gasolene is immediately evaporated and mixed with definite quantities of air and in which the mixed gasolene 20 vapors and air are passed under pressure to a regulator bell and delivered therefrom through delivery pipes or mains.

The invention also has for its object to 25 provide a generator wherein the gasolene will be fully vaporized and mixed with air under conditions that will prevent the temperature within the carbureter or mixing and vaporizing mechanism from dropping below a definite degree.

30 The invention further provides means whereby either dry gas may be generated or wet gas, or both.

The invention further resides in those 35 novel details of construction, combination and arrangement of parts, all of which will be first fully described, and then be specifically pointed out in the appended claims, reference being had to the accompanying drawings, in which:—

40 Figure 1, is a side elevation of one form of the invention, wherein the entire mechanism is embodied in a single machine. Fig. 2, is a vertical section on the line 2—2 of Fig. 1. Fig. 3, is a vertical section on the line 3—3 of Fig. 2. Fig. 4, is a vertical section on the line 4—4 of Fig. 2. Fig. 5, is a detail side elevation of the conveyer drive ratchet and pawl mechanism. Fig. 6, is a detail perspective view of one of the conveyer buckets. Fig. 7, is a detail perspective view of the swinging gasolene distributor. Figs. 8 and 9, are detail views of the rotary vaporizer. Fig. 10, is a detail sec-

tion (on an enlarged scale) of the zigzag carbureter. Fig. 11, is a detail section of 55 the automatic thermally operated cut-off device. Fig. 12, is a cross section of the swinging distributor. Fig. 13, is a detail view of one of the adjustable bucket dumping members.

Referring now to the accompanying drawings in which like letters and numerals of reference indicate like parts in all of the figures, it will be seen that upon a suitable support 1, the blower and carbureter casing 2 is set. The casing 2 is closed by a head 3 65 which may be bolted to the casing 2 through the flange 5.

4 is a plate formed with the head 3 and spaced therefrom at 6, as shown. The plate 4 has a bearing 7 for the blower shaft 9, one end of which engages a plug bearing 8, and the other is held in a bearing 10, carried by an L-pipe 11, one end of which pipe is threaded into the rear wall of the casing 2 and communicates with the passage 14 75 formed by the rear wall of the casing and by the integrally formed pipe-like wall 12, a removable plug 13 being provided for gaining access to the passage 14, in alignment with the blower shaft. The casing 2 has a 80 passage 15 that communicates with the exit end 16 of a zig-zag carbureter 17, the entrance end 18 of which is held in communication with the pressure chamber 81, formed by the blower casing 2, and an inner casing 85 19 that houses the blower blades 21. The inner casing 19 is divided transversely by a partition 20 to form a chamber for the pipe 11, the casing 19, member 21, and partition 20 being rigidly united to turn as one. 90 Upon the shaft 9, between the bearings 7 and 8 is a sprocket wheel 22, over which and over the sprocket 23 on the drum shaft 25 an endless chain 24 passes.

The drum shaft 25 is held in a bearing in 95 the head 3 and in a bearing 27 on a bracket 28, the drum receiving the cable 29 that is connected with the weight 30. A handle (see dotted lines in Fig. 1) is provided for winding up the cable on the drum.

The gasolene tank 31 of the machine is mounted on the blower casing 2, and has a hood 32 to cover the bucket wheel 35 that is mounted on a shaft 34 that is held in a bearing 33 in the tank wall.

100 The buckets 36 are pivoted to pins 37 on

the wheel 35 and have arms 38 to engage the adjustable trip pins 82 on the inner walls of the hood 32. The trip pins 82 are secured one on the rear wall and one on the front wall of the hood 32 so that one of the pins 82 will engage one set of buckets and the other pin 82 will engage the other set of buckets, one of the pins 82 being located in advance of the other, as shown in Fig. 4 of the drawings. The trip pins 82 are adjustable to tip the buckets at different angles and allow only a more or less partial emptying thereof. Funnels 39 and 44 receive the contents of the buckets 36 as the wheel 35 turns through the medium of devices hereinafter referred to. The funnel 44 is piped up through pipe 45 (having a cutoff cock 46) as clearly shown in Fig. 2 of the drawings. The pipe 45 passes through the passage 14 and the pipe 11 and has its outlet 47 arranged to discharge onto a fan 49 at the mouth of the cap 48 of the pipe 11. The suction of air past the fan 49 causes its rotation and the gasoline dropped from the pipe 47 onto the fan 49 will be whirled or scattered to render it more easily volatilized.

The regulator casing 50 is supported over the casing 2 by the integrally formed pipe sections 51 and 53, which form continuations of the passages 14 and 15, respectively. The pipe section 51 has its bore opening centrally into the casing 50, while the pipe 53 communicates with the casing 50 near the outer wall thereof.

A pipe 52 is held centrally within the casing 50 and registers with the central opening, while a pipe 54 is held over the opening into the pipe section 53. The central pipe 52 extends to near the top of the casing 50 and carries a hood 58 whose lower edge is cut into V-shaped portions 59 to dip into a tank 56 in the top of the gas bell 55, which bell 55 has a tube 57 to slip over the pipe 52 and form a bearing for the bell. The pipe 54 extends to near the top of the bell 55 when down. The pipe 52 is slotted at the top to afford communication between the interior of the hood 58, as shown in Fig. 2 of the drawings. Air is admitted into the casing 50 above the bell 55 through an elbow 60 having filter screens 61, as shown.

62 designates the gas outlet pipe within the bell 55 that passes through the casing 50 and terminates in an outlet 63 to which the gas delivery pipe, or main (not shown) joins, filter screens 64 being provided for the usual purposes.

65 is a pipe which conveys the gasoline from the pump 66 to the tank 31, the pump 66 receiving its supply from a storage tank (not shown) through a pipe 67.

68 designates a U-tube or pipe, one arm of which connects with the tank 31, while the other arm carries a thermally opened

cutoff 69 which is in turn connected with the pipe 67, the cutoff 69 consisting of a casting having a fusible partition 70 adapted to melt at a definite temperature, say, at 150 degrees Fahrenheit, and permit passage of the gasoline through the U-pipe to the pipe 67 and back to the storage tank. Should fire occur in the room containing the machine, the heat will fuse the soft metal 70 of the cutoff 69 and permit the gasoline from the tank 31 to return to the underground storage tanks via pipe 67 and thus prevent an explosion. The fusible plugs of the perforated partition 70 are melted by the heat and open the passage through the plug 69 to the pipe 67 under the conditions stated.

The elevator shaft 34 carries a ratchet wheel 71 with which a pawl 72 co-operates. The pawl 72 is secured to a disk 73, having a slot 74, by a bolt 75 whereby the throw of the pawl 72 may be varied to vary the action of the conveyer and deliver predetermined quantities of gasoline to the several funnels 39 and 44 respectively. The disk 73 is mounted on a stub shaft 76 that has a sprocket 79 around which and around a sprocket 78 on the drum shaft 25, the drive chain 77 passes. By adjusting the stroke of the pawls 72, the number of buckets-ful of gasoline delivered into the respective funnels 39 and 44 may be varied to suit the working conditions.

The funnel 39 is piped-up by a pipe 40 with the distributor 41, a throttle valve 43 being provided after the pipe passes through the bottom 80 of the gasoline tank 31. A vent pipe 84* is provided for the tank 31.

The distributor 41 is a trough-like member that is pivoted to the pipe 40, as shown in Figs. 7 and 12, and is provided with a plurality of apertured teats through which the contents of the distributor are discharged, see Figs. 7 and 12.

Operation: The operator winds up the cable 29 on the drum 26 and pumps gasoline into the tank 31; by the use of the pump 66, the weight 30 then turning the drum shaft in the direction of the arrow in Fig. 1, sets the blower 21 and elevator 35 into operation. The elevator delivers measured quantities (bucket-ful) of gasoline to the funnels 39 and 44, that delivers into the funnels 39, flowing into the distributor 41, and through the zigzag carbureter 17, where it flows down along the corrugated bottom plates of the carbureter 17. The gasoline in the carbureter 17 flowing down on the corrugated bottom plates thereof is vaporized by the passing air and gas currents.

The blower causes air to be sucked from the inlet 60 into the casing 50 above the bell 55 under the hood 58, from which it flows up into the pipe 52, from which pipe 52 it flows into the passage 14, and from thence into the pipe 11. As it leaves the pipe 11

- through the cap 48 the air is sucked into the chamber 84 of the blower 21, from whence the blower forces it into the chamber 81. The blower 21 when in operation 5 causes a reduced pressure in the chamber 84, thus vaporizing the gasoline that emerges from the pipe 47, the combined vaporized gasoline and air is what passes through the blower into the chamber 81, where it will be 10 under a positive pressure. The air is forced from the chamber 81 to the zig-zag carbureter 17, where it is enriched by gasoline from the distributor 41. The carbureted air then passes into the passage 15 and from 15 thence into the bell 55, via the pipe 54. Should more gas be generated than is being consumed at the burners the bell 55 will rise and gradually close off the air supply by immersing the openings 59 of the hood 58. 20 At this time also a drag occurs on the blower 21 thereby slowing it down, and at the same time the flow of carbureted air through the blower and carbureter is proportionately stopped. Hence proportionately less gas is 25 delivered to the bell 55. When the bell 55 is full and air is totally cut off, retarding influence on the blower, will suffice to completely stop the blower and elevator until the gas within the bell 55 has been withdrawn through 30 the pipe 62, and the air passage is again open. Thus it will be seen that my improved gas generating apparatus is self-regulating, will give a gas of constant richness and one in which the air and gasoline vapor bear a 35 constant relation to one another.
- The zig-zag carbureter 17 alone may be used by closing the valve 46, or the rotary carbureter alone may be used by closing the valve 43, or both carbureters may be used at 40 the same time, when both valves 46 and 43 are open. Thus a gas with but a limited amount of gasoline vapor may be provided or an enriched gas may be formed, as desired. Furthermore the water in casing 2 45 which is kept in constant circulation by the blower 21, will thereby keep the contents of the chamber 84 and carbureter 17 at an even temperature. In the practical operation of my apparatus as demonstrated by actual 50 practice and tests and the conditions ordinarily met with in practice, freezing of the water in the chamber 84 does not occur.
- By corrugating the bottom walls of the carbureter 17 the liquid will be prevented 55 from running down along one side or the other should the apparatus not be held exactly level and by pivoting the distributor 41 any unlevelness of the machine will be compensated.
- 60 From the foregoing description taken in connection with the accompanying drawings it is thought the complete construction, operation and advantages of the invention will readily appear to those skilled in the art, 65 and I desire to say that slight changes in the details of construction and arrangement of parts may be made without departing from the invention.
- In order to render the operation of the blower more easy, holes 85 are provided in the blades 21, see Fig. 2.
- It is essential in a dry evaporation process that the gasoline be distributed over broad areas in order to evaporate rapidly and by employing the corrugated bottom in the carbureter, the gasoline is forced to an exact and wide distribution, which by no other means is obtainable on account of the capillary attraction of the gasoline molecules.
- What I claim is:—
1. A carbureting apparatus comprising a first and a second casing, a blower within the second casing, a regulator bell within the first casing, an air chamber above the regulator bell, said first casing having an air inlet to said air chamber, means for conveying air from said air chamber of the first casing into the second casing, means for conveying carbureted air from the second casing back into the first casing and beneath the regulator bell, means within the first casing and coöperating with the regulator bell for controlling the admission of air into the second casing, means for carbureting the air as soon as it passes from the first casing into the second casing, means for further carbureting said air before it leaves the second casing to pass it into the first casing beneath the regulator bell, said first named carbureting means comprising a fan, and means for dropping gasoline onto the fan.
  2. A carbureting apparatus comprising a first and a second casing, a blower within the second casing a regulator bell within the first casing, an air chamber above the regulator bell, said first casing having an air inlet to said air chamber, means for conveying air from said air chamber of the first casing into the second casing, means for conveying air from the second casing back into the first casing and beneath the regulator bell, means within the first casing and coöperating with the regulator bell for controlling the admission of air into the second casing, means for carbureting the air as soon as it passes from the first casing into the second casing, means for further carbureting said air before it leaves the second casing to pass it into the first casing beneath the regulator bell, said first named carbureting means comprising a fan, means for dropping gasoline onto the fan, said second mentioned carbureting means comprising a stationary member having a zigzag passage through which the air and gas pass in their travel from the second casing back to the first casing, and means for admitting gasoline into said zigzag passage.

3. In a carbureting apparatus, a blower casing, a gas bell casing supported thereover, said casings having ports in communication with one another, a gas bell within the gas bell casing, and a blower within the blower casing, said blower comprising blades and a casing surrounding said blades and rotatable therewith, a pipe within said surrounding casing in communication with one of said ports of said blower casing through which the blower sucks air from the bell casing, a stationary carbureter within the blower casing through which the blower forces the air, said stationary carbureter having communication with one of the ports of the bell casing, and means for conveying gaseous fluid from said last named port beneath the gas bell, means for actuating said blower, means for admitting gasoline into said carbureter to carburet the air in its passage through the carbureter, and means for actuating said last named means from the blower actuating means.

4. In a carbureting apparatus, a gas bell casing and a blower casing, said gas bell casing having an air chamber, means within the blower casing for withdrawing air from the gas bell casing into the blower casing and returning it from the blower casing into the gas bell casing beneath the gas bell, means for carbureting the air as it enters the gas bell casing, said last named means comprising a gasoline casing, mounted adjacent to the blower and gas bell casing, a gasoline feeding means within said gasoline casing, a receiver for receiving gasoline from said gasoline feeding means, a pipe connected with the receiver and discharging within the blower casing to convey gasoline into the blower casing to carburet the air as it enters the blower casing.

5. In a carbureting apparatus, a gas bell casing, and a blower casing, said gas bell casing having an air chamber, means within the blower casing for withdrawing air from the gas bell casing into the blower casing and returning it from the blower casing into the gas bell casing beneath the gas bell, means for carbureting said air as it leaves the blower to pass back into the gas bell casing beneath the gas bell, said last named means comprising a gasoline casing, a gasoline feeding means within the gasoline casing, a receiver to receive the gasoline from the feeding means, a carbureting means including a carbureter casing, and means for conveying the gasoline from the receiver to the carbureting means.

6. In a carbureting apparatus, a gas bell casing, and a blower casing, said gas bell casing having an air chamber, means within the blower casing for withdrawing air from the gas bell casing into the blower casing and returning it from the blower casing into the gas bell casing beneath the gas bell,

means for carbureting said air as it leaves the blower to pass back into the gas bell casing beneath the gas bell, said last named means comprising a gasoline casing, a gasoline feeding means within the gasoline casing, a receiver to receive the gasoline from the feeding means, a carbureter casing, means for conveying the gasoline from the receiver to the carbureter casing, a second receptacle within the gasoline casing, pipe connections between said second receptacle and the blower casing to admit gasoline into the blower casing to mix with the air before it passes through the blower.

7. In a carbureting apparatus, a gas bell casing, and a blower casing, said gas bell casing having an air chamber, means within the blower casing for withdrawing air from the gas bell casing into the blower casing and returning it from the blower casing into the gas bell casing beneath the gas bell, means for carbureting said air as it leaves the blower to pass back into the gas bell casing beneath the gas bell, said last named means comprising a gasoline casing, an elevator within the gasoline casing, a receiver to receive the gasoline from the elevator, a carbureter casing, means for conveying the gasoline from the receiver to the carbureter casing, a second receptacle within said gasoline casing, pipe connections between said second receptacle and the blower casing to admit gasoline into the blower casing to mix with the air before it passes the blower, and a single regulating device co-operating with the gas bell for controlling the flow of air from the bell casing into the blower casing and simultaneously controlling the action of the carbureting means.

8. In a carbureting apparatus, a casing, a blower within said casing, said casing having an inlet, and an outlet, a stationary carbureter within said casing and having a longitudinally fluted or corrugated bottom, said carbureter having an entrant end to receive air from the blower and having an exit end in communication with the exit of the blower casing, and means for admitting gasoline into said carbureter to carburet the air as it passes therethrough.

9. In a carbureting apparatus, a casing, a blower within said casing, said casing having an inlet, and an outlet, a stationary carbureter within said casing and having a longitudinally fluted or corrugated bottom, said carbureter having an entrant end to receive air from the blower and having an exit end in communication with the exit of the blower casing, means for admitting gasoline into said carbureter to carburet the air as it passes therethrough, said means comprising a gasoline supply pipe and a distributor secured to the end thereof within the carbureter.

10. In a carbureting apparatus, a casing, a

blower within said casing, said casing having an inlet and an outlet, a stationary carbureter within said casing and having a longitudinally fluted or corrugated bottom, said carbureter having an entrant end to receive air from the blower and having an exit end in communication with the exit of the blower casing, means for admitting gasoline into said carbureter to carburet the air as

it passes therethrough, said means comprising a gasoline supply pipe and a swinging distributor carried thereby within the carbureter.
